ANTENNA

Allen S. Dunbar, Brookline, Mass., assignor, by mesne assignments, to the United States of America as represented by the Secretary of War

Application January 3, 1946, Serial No. 638,887

10 Claims. (Cl. 250—33.63)

This invention relates to antennas and more particularly to an antenna adapted to produce a predetermined radiation pattern.

It is frequently desirable to cause the radiation emanating from an antenna to illuminate a portion of space with a predetermined radiation pattern. It is particularly desirable in certain instances, for example in radio object locating systems in which a single antenna may serve both for transmission of electromagnetic radiation and for reception of echoes, to produce a radiation pattern such that objects in a given plane and having like reflectivity will produce equal echoes regardless of the location of the objects in that plane. Such antennas are particularly useful in airborne radio echo detection apparatus when it is desired that echoes from ground objects of like reflectivity shall have the same intensity regardless of the locations of the objects. It may readily be proved that the radiation intensity from such an antenna should be proportional to the $csc^2 A$ where angle A indicates the angle of radiation as measured from a horizontal plane through the antenna.

Therefore, among the objects of this invention are: to provide an antenna which will produce a csc^2 radiation pattern; to provide an antenna which will produce a desired predetermined directional radiation pattern; and to provide such an antenna adapted for utilization with a line source of radiation.

Further objects, advantages, and novel features of the invention will become apparent from the description contained herein wherein reference is made to the accompanying drawing in which:

Fig. 1 is a perspective view of a preferred embodiment of the invention, and

Fig. 2 represents a side view of one of the wave guide plates of the antenna structure.

It is contemplated in the invention to feed a parallel plate wave guide assembly with electromagnetic energy having polarization parallel to the plane of the wave guide plates. The wave guide assembly alters the phase velocity of energy traveling therethrough, and suitable shaping of the guide surfaces produces a desired radiation pattern.

Referring now to Fig. 1, a hollow pipe wave guide 5 introduces electromagnetic energy from source (not shown) to a parabolic pillbox 6. Pillbox 6 is constructed of parallel wave guide plates 8 and a parabolic cylindrical reflecting surface 7 substantially normal to the plates. Energy from wave guide 5 is introduced near the focus of the inner parabolic surface of reflector 7 and radiation having a substantially straight line phase front is secured along pillbox aperture 9. Aperture 9 may be flared, if desired, for impedance matching and energy directing purposes. It will be clear to those skilled in the art that aperture 9 may be shaped so that energy emanating therefrom provides substantially a line source of radiation which is normal to the axial plane of the parabolic cylindrical reflecting surface 7.

For convenience in description, line 10 along aperture 9 may be assumed as the line source of radiation. It will

also be assumed that it is desired to illuminate a ground plane with a csc^2 radiation pattern. The antenna structure shown in Fig. 1 and the corresponding end view of Fig. 2, in which line source 10 is oriented parallel to the ground plane, indicate the correct orientation of the antenna to accomplish this result. The energy emanating from source 10 is polarized in a particular plane or along particular lines, which, in this instance, are perpendicular to the pillbox plates 8 and likewise to line 10. A plurality of parallel plate wave guides 11 are formed by an assembly 12 of conductively surfaced plates 13. Plates 13 may be secured to end members 14 and 15 attached to a supporting structure (not shown) which also supports pillbox 6 and wave guide 5. Bracing members may be provided for pillbox 6 on its upper plate 8 as shown. The conductive surfaces of the plurality of parallel plate wave guides 11 thus formed are oriented parallel to the plane of polarization of the radiant energy, that is, perpendicular to line source 10.

Referring now to Fig. 2, the leading or near edges 16 of these conductive surfaces, that is, the edges nearest line source 10, are circular in shape so that each edge lies on a circular cylindrical surface having line 10 as its axis. The far edges 17 of these conductive surfaces, that is, the edges farthest from line source 10, are shaped to produce the desired radiation pattern effect, as will appear more fully hereinafter. Edges 17 lie on a cylindrical surface, not necessarily circular, having line elements parallel to line 10.

An energy phase front departing from line source 10 is circularly cylindrical in configuration, and therefore energy reaches edges 16 of parallel plate guides 11 in phase.

The arrowed lines in Fig. 2 display directions of travel of the energy. As is well known, the spacing between plates 13 will determine the phase velocity of the electromagnetic energy passing therebetween. Because the energy leaving source 10 reaches the leading edges 16 of the wave guides along a phase front, the phase front will undergo no alteration and the energy will continue to travel along straight lines as illustrated by arrowed lines 18 and 19. However, upon passing from wave guides 11 into the atmosphere beyond edges 17 at which the phase velocity again changes, the phase front will undergo an alteration due to the varying path lengths within wave guides 11. Since phase velocity in the parallel plate wave guides 11 is greater than the velocity of electromagnetic energy in air, the phase front emanating from any portion of the wave guide structure 12 along the far edges 17 will undergo a change in direction toward the normal of the cylindrical surface on which edges 17 lie. The shape of edges 17 may be computed by direct mathematical or graphical methods. For example, a radiation pattern of the csc^2 type may be achieved by computing the shape of edges 17 utilizing analogous optical methods. Since the ratio of the velocity of radiation in the guides to the velocity of radiation in air may be determined from the spacing between the plates, a corresponding coefficient of refraction or dielectric constant is readily obtained. An equation for the design of the outer edges 17 is:

$$\log_e \frac{r}{r_0} = \int_{\alpha_0}^{\alpha} \frac{\sin(\theta - \alpha)}{u - \cos(\theta - \alpha)} d\alpha$$

for producing the desired csc^2 pattern. The upper portions of edges 17 are then nearly hyperbolic, the focus of the hyperbola being at line 10. In the equation as indicated for a chosen point 21, r is the radial distance from line 10 to outer edge 17; r_0 is a constant; α is the angle that energy incident on the antenna lens makes

with the horizontal; θ is the angle between the direction of travel of energy emerging from the lens and the horizontal, in other words the direction of the emerging beam; and u is the equivalent dielectric constant of the antenna lens system.

An advantage of the described embodiment is its production of a $\csc^2 \theta$ pattern of radiation over large angles of elevation, heretofore not readily attainable.

Although the description herein has been with reference to the transmission of electromagnetic energy, it will be understood by those skilled in the art that the antenna may equally well be used for purposes of reception with like directive characteristics.

Furthermore, it will be apparent to those skilled in the art that there are many variations of the invention. Therefore, it is not desired to restrict the scope of the invention to the precise embodiment herein described but to include all modifications or equivalents which conform to its spirit.

What is claimed is:

1. An antenna for the transfer of electromagnetic energy, including a plurality of substantially planar and parallel conductive plates separated substantially equal distances to form wave guides, each said plate having a first curved edge and a second curved edge, said first curved edges lying on a first cylindrical surface, the axis of said first cylindrical surface being perpendicular to the planes of said plates, said second curved edges lying on a second cylindrical surface, the axis of said second cylindrical surface also being perpendicular to the planes of said plates, the width of said plate, between said curved edges, varying from point to point along the length of said plate, whereby energy having a given field pattern polarized in the plane of said conductive plates and incident on said first cylindrical surface is refracted in passing through said wave guides to form a desired field pattern upon emerging from said second cylindrical surface.

2. The antenna of claim 1 wherein one of said cylindrical surfaces is circularly cylindrical.

3. An antenna as defined in claim 1, wherein the first cylindrical surface is circularly cylindrical, and further including a source of electromagnetic waves and means for causing said waves to form a cylindrical wavefront about the axis of the first circularly cylindrical surface with the said waves polarized parallel to the said conductive plates.

4. An antenna as claimed in claim 3, wherein the second said cylindrical surface corresponds to the equation:

$$\log \frac{r}{r_0} = \int_{\alpha_0}^{\alpha} \frac{\sin(\theta-\alpha)}{u-\cos(\theta-\alpha)} d\alpha$$

wherein r is the radial distance from the axis of said circularly cylindrical surface to a point on said second cylindrical surface, r_0 is a constant, α is the angle that a ray of said electromagnetic energy incident on said circularly cylindrical surface makes with a line bisecting said circularly cylindrical surface, said line being perpendicular to the axis of said circularly cylindrical surface, θ is the angle that a ray emerging from said second cylindrical surface makes with said bisecting line, and u is the equivalent dielectric constant of said wave guides, whereby an approximately $\csc^2 \theta$ field pattern of radiation over a large range of angles in the planes of said plates is derived from the electromagnetic energy having a cylindrical wavefront about the axis of said first circularly cylindrical surface.

5. A plurality of plate elements having conductive surfaces symmetrically placed and substantially equally spaced to form parallel plate wave guides, each plate having a first curved edge and a second curved edge, said curved edges being opposed to each other, the width of said plate, between said curved edges, varying from point to point along the length of said plate, the corresponding curved edges of each consecutive pair of said plates de-

fining opposed curved orifices of the wave guide formed between said plates, said wave guide including said orifices being substantially free from conductive material, whereby electromagnetic energy, having a given field pattern and polarized parallel to said plate elements incident on said first curved edges, is refracted in passing through said wave guides to form a desired field pattern upon emerging from said second edges.

6. A metallic lens system for altering the field pattern of electromagnetic energy, including a plurality of parallel plates forming wave guides, each plate having a first curved edge and a second curved edge, said curved edges being opposed to each other, the width of said plate, between said curved edges, varying from point to point along the length of said plate, whereby electromagnetic energy polarized parallel to said plates and incident on said first curved edges is refracted in passing through said wave guides.

7. A lens comprising a pair of spaced parallel flat conductive members having a set of corresponding circular longitudinal edges and a set of corresponding hyperbolic longitudinal edges, said circular edges being parallel and said hyperbolic edges being parallel.

8. A lens comprising two spaced parallel flat conductive members, at least one of said members having two oppositely-disposed longitudinal edges, the curvature of one of said edges being circular, the curvature of the other of said edges being hyperbolic, the other of said members being of at least equal dimensions and area as said one of said members whereby the space included between said two members will be of uniform thickness determined by the spacing between said parallel members and will have two oppositely-disposed longitudinal contours having curvatures determined by the said oppositely-disposed longitudinal edges of said one member.

9. An antenna for the transfer of electromagnetic energy including a plurality of substantially planar and parallel conductive plates separated substantially equal distances to form wave guides, each said plate having two oppositely-disposed longitudinal edges, at least one of said edges having a curvature concave throughout a major portion of its length and convex throughout the remainder of its length near one end of said plate, the corresponding longitudinal edges of all said plates being substantially parallel, the set of curved longitudinal edges of said plates lying on a cylindrical surface the longitudinal axis of said cylindrical surface being perpendicular to the planes of said plates, the other set of longitudinal edges of said plates lying on a smooth surface the longitudinal axis of said smooth surface also being perpendicular to the planes of said plates, the width of each of said plates between said oppositely-disposed longitudinal edges varying from point to point along the length of said plate, whereby energy having a given field pattern, polarized in the plane of said conductive plates and incident on one of said surfaces is refracted in passing through said wave guides to form an approximately cosecant squared pattern of radiation over a large range of angles in the planes of said plates.

10. A radio wave refractor for linearly polarized radio waves, comprising a first conductive flat plate, a first edge of said plate having a circularly concave curvature and a second edge of said plate, oppositely-disposed to said first edge, having a hyperbolically concave curvature, the area of said first plate being at least coextensive with the area between said first and said second edges and straight lines joining corresponding ends of said edges, a second conductive flat plate disposed in a plane parallel to that of said first plate, the lengths of said circular and hyperbolic edges of said first plate both being large with respect to said separation between said plates, said second plate being at least coextensive with the normal projection of said first plate on the plane in which said second plate is disposed, said plates defining

75

between them a wave guide having a first circularly curved concave orifice and a second oppositely-disposed orifice which is hyperbolically curved and concave, whereby linearly polarized radio waves having a polarization parallel to the planes of said plates, and a particular shape of waveform, when incident on one of said orifices and directed generally toward the other of said orifices, will be refracted in passing through said wave guide to form a desired field pattern upon issuing from the other of said orifices.
